UNITED STATES PATENT OFFICE.

ASHFORD L. QUINN, OF MAYO, SOUTH CAROLINA, ASSIGNEE OF ONE-HALF TO BALL E. WILKINS, OF MAYO, SOUTH CAROLINA.

RAIL-LIFTING ROD FOR SPINNING-FRAMES.

1,056,201.

Specification of Letters Patent. Patented Mar. 18, 1913.

Application filed July 30, 1912. Serial No. 712,350.

To all whom it may concern:

Be it known that I, ASHFORD L. QUINN, citizen of the United States, residing at Mayo, in the county of Spartanburg and State of South Carolina, have invented certain new and useful Improvements in Rail-Lifting Rods for Spinning-Frames, of which the following is a specification.

This invention relates to an improvement in rail lifting mechanism for spinning frames.

The primary object of the invention is to provide a lifting bar which is actuated by the builder motion of such construction that the sleeves which are supported by the rails of the spinning frame will be cleaned by the action of the spinning rail lifting rod.

The invention contemplates the providing of the lifting rod with means for keeping the sleeves of the fixed rails clean, the rod removing the lint which normally enters said sleeve, a portion of the rod being removed to accommodate foreign material which may enter said sleeve.

The drawing shows a portion of a ring spinning frame of the usual construction which includes the fixed rail 10 on which is mounted for movement the ring rail 11 the spindles 12 being supported in the usual manner. While the lifting mechanism is shown as applied to this type of spindle rails attention is called to the fact that the invention is applicable to any type of spinning frame. The ring rail is lifted by the rod 14 and may be actuated by any suitable builder mechanism, there being shown a toggle lever 15 in the drawing which is actuated by the bar 16, the lever 15 being provided with a slot 17 which receives the lower end 18 of the rod 14. The fixed rails 10 receive bearing sleeves 19 which are maintained in position by set screws 20, the rods 14 passing through said sleeves, the upper terminals being connected to the ring rail 11. It has been found in practice that lint and other foreign material will enter the sleeves 19 and interfere with the reciprocation of the rods 14. It is essential that the rods impart a steady lifting motion to the ring rail, especially on fine numbers this steady movement of the rod not being possible where the lint and foreign material enters the sleeve as the obstruction in the

sleeve serves to retard the rod in its movement, imparting a "jerky" movement to the rod instead of the desired steady lift. To maintain these sleeves clean at all times and to allow for a steady movement of the lifting rod, said rod is formed with a spiral groove which is cut in such manner that as the rod is lifted and lowered the edges of the groove will wipe the bearing clean, said groove receiving the foreign matter within the sleeve. It will be noted by this construction that the sleeve may be at all times maintained cleaned, allowing for a steady upward thrust of the rod. Particular attention is called to the fact that this cleaning of the bearing sleeve is accomplished without adding to the construction of either the builder mechanism or the spinning frame.

What is claimed is:

1. A spinning frame, including fixed rails, sleeves supported by said rails, a movable rail, a rod disposed to reciprocate within the sleeves and move the movable rail, the contacting faces of the rod and sleeve being provided with a spiral receptacle open at both ends of the sleeve to provide a lint pocket at such contacting faces to prevent the binding of the lint between the sleeve and rod.

2. A spinning frame including fixed rails, sleeves supported by said rails, a movable rail, a rod disposed to reciprocate within said sleeves, said rod being formed with a groove, said groove coacting with the sleeve to form a receptacle for and to receive the lint within the pocket formed by the groove and the adjacent portion of the sleeve. 90

3. A spinning frame including fixed rails, sleeves supported by said rails, a movable rail, a rod disposed to reciprocate within said sleeves, said rod being formed with a spiral groove, said groove serving to clear the sleeve of the lint and to simultaneously form a receptacle to receive the lint to prevent the binding effect of the lint between the rod and sleeve. 95

In testimony whereof I affix my signature in presence of two witnesses.

ASHFORD L. QUINN.
